CLAIM

The ornamental design for an applicator, as shown and described.

DESCRIPTION

FIG. 1 is a front right perspective view of an applicator in accordance with an embodiment of the claimed design; FIG. 2 is a front elevation view of the design of FIG. 1; FIG. 3 is a rear elevation view of the design of FIG. 1; FIG. 4 is a right side elevation view of the design of FIG. 1; FIG. 5 is a left side elevation view of the design of FIG. 1; and, FIG. 6 is a top plan view of the design of FIG. 1. The bottom views of the design of FIG. 1 are omitted as they form no part of the claimed design. The labels used herein to describe orientation (e.g., front, rear, left, right) are merely for reference and are not intended to limit the interpretation of the design.
